UNITED STATES PATENT OFFICE.

SAMUEL F. HOLMES, OF LOS ANGELES, CALIFORNIA.

PERMUTATION-PADLOCK.

1,018,616.

Specification of Letters Patent. Patented Feb. 27, 1912.

Application filed March 7, 1911. Serial No. 612,805.

To all whom it may concern:

Be it known that I, SAMUEL F. HOLMES, a citizen of the United States, residing at Los Angeles, in the county of Los Angeles and 5 State of California, have invented new and useful Improvements in Permutation-Padlocks, of which the following is a specification.

This invention relates to improvements in 10 locks, and particularly to portable devices or locks of the padlock type, and it is the object of the invention to provide a permutation lock well guarded against easy picking, which will not require the use of the 15 key.

It is also an object of the invention to provide a padlock with a combination mechanism for permitting of the unlocking or locking of the device.

20 In the accompanying drawing forming a part of this specification, Figure 1 is a perspective view of the improved permutation padlock. Fig. 2 is a vertical transverse sectional view through the same. Fig. 3 is a 25 central view taken longitudinally of the device and at right angles to the section of Fig. 2. Fig. 4 is a detail perspective view of one of the tumblers of the lock. Fig. 5 is a detail sectional view through a portion 30 of the locking casing showing the outer actuating tumbler of the combination and the exterior knob connected therewith for turning it. Fig. 6 is a detail view partially in section and partially in side elevation of the 35 two part locking bolt employed in connection with the combination mechanism.

The details of the invention will now be more particularly described, reference being had to the accompanying drawing, in 40 which—

1 indicates a lock casing, 2 a shackle pivoted therein as at 3, and 4 a bolt for securing the shackle in locked position. The casing and shackle may be of any desired or ordinary type suitable for padlocks or similar portable locks, and the said shackle is provided at its free end with a notch 5 adapted to be engaged by a lip or projection 6 formed upon the bolt 4. The end of the shackle is 45 adapted to extend into a slot 7, formed in the casing 1, its extremity being provided with a curved portion 8, adapted to slide or force by the lip 6 of the bolt.

The bolt 6 is preferably made in the form 50 of a bifurcated arm pivoted by a pivot pin

9, within the casing 1, while within the bifurcated portion of the bolt 4 is mounted a bolt actuating arm or lever 10 having a projecting nose 11, adapted to bear upon one side of the bolt 4 for drawing the bolt out of locked position at proper intervals. The free end of the lever 10 is provided with a laterally extending flange 12, which rests upon and engages the tumblers of the combination portion of the lock.

A spring 13, preferably fulcrumed upon the pivot pin 9, bears at one end against the lip 6 of the bolt 4 and at its other end against the flange 12 of the lever 10, the tendency of the spring being to keep the bolt 4 against the nose or projection 11 of the lever 10 under spring tension. The said spring, however, will yield sufficiently to permit the bolt 4 to be forced backwardly by the end of the shackle 2 when the said shackle is to be locked in position. The said spring of course will cause the lip 6 to automatically engage the notch 5 of the shackle when the said shackle is closed. The bolt mechanism is also preferably provided with a second spring 14 which is generally fulcrumed upon the pin 9 and has one end extending into a recess 15 formed in the adjacent wall of the casing 1. The other end of said spring bears upon the edge of the flange 12 upon the lever 10. The said spring insures the riding of the said flange 12 upon the edges of lock tumblers and when the depression in the tumblers permit the said flange 12 to be depressed, the said spring 14 will force the lever 10 downwardly so as to withdraw the bolt 4 from its engagement with the shackle 2.

The flange 12 is adapted to coöperate with a number of disks or combination tumblers as 16, 17 and 18. The disks 16, 17 and 18 are preferably made similar to those of the ordinary permutation lock, and the outer disk near the face of the lock as 16, is carried by a shaft 19 which projects through the front of the lock and has rigidly secured thereto an operating knob 20. The said knob 20 is provided with a flange 21 having an indicator mark or notch 22 formed thereon.

Numerals as at 23 are provided upon the face of the lock adjacent to the flange 21 so that by turning the knob 20 the notch 22 may be made to come opposite first one number and then another, to work out the 110

combination for opening the lock. All of the disks within the lock are provided with depressions as 24, which, when brought beneath the flange 12 simultaneously, will permit of the dropping of the lever 10 under the action of the spring 14 for unlocking the shackle. The disk 16 is provided with an actuating projection 25, adapted to engage a projection 26, located upon the adjacent intermediate disk 17. Both of the said intermediate disks 17 are provided with projections or detents of similar character and the outer disk 18 is provided with a projection on its inner surface only, as clearly shown in Fig. 2, the arrangement of all the projections upon the various disks being such that by turning the knob 20, first a given number of times in one direction and then a given number of times in another direction, and so back and forth for completing the combination, all of the disks may be turned to bring their notches 24 in alinement beneath the flange 12 of the lever 10.

It will be apparent that the projections may be arranged differently upon the disks to make different combinations for different locks, or the disks may be altered in their arrangements in the same lock so that the combination may be changed. The disks 17 and 18 are preferably carried by a shaft 30, secured to the back of the casing and project inwardly in alinement with the shaft 19, which carries the knob and the disk 16. Thus when the face plate of the casing is fastened in position, the combination mechanism will be in readiness for operation.

The structure of the bolt mechanism is particularly adapted for padlock use in that when the combination is thrown off the padlock can be locked by forcing the shackle inwardly past the spring pressed bolt 4. The said shackle is then automatically locked by the action of the spring 13. It can only be unlocked then, by bringing all of the depressions or recesses 24 of the disks in alinement beneath the flange 12 of the lock lever 10. The operation of the mechanism has been fully described in setting forth the features of the invention and will be readily understood.

What I claim is:

1. A pad lock mechanism, comprising a pivoted shackle, a spring actuated bolt adapted to automatically lock the shackle upon its being closed, a lever pivoted adjacent to said bolt and having means engaging the bolt up on one side for rocking it out of engagement with the shackle, said bolt being free to move in the other direction irrespective of said lever, a series of disks adapted to be operated from the exterior of the lock for controlling the action of said

lever, and spring means for normally holding the said lever against the said disk.

2. A permutation pad lock, comprising a casing carrying a pivoted shackle, locking means therefor comprising a pivoted bolt, a controlling lever pivoted coaxially therewith and having an arm engaging the bolt and capable of withdrawing the same, a spring for normally keeping the bolt against said arm, disks forming tumblers for controlling the action of the said lever, and a spring normally forcing the said lever against the said tumblers, the structure being such that the bolt may be forced inwardly to lock the shackle when the lever is held in locked position by the said tumblers, the said lever being capable of withdrawing the bolt when the tumblers permit.

3. A permutation pad lock, comprising a casing, a shackle pivoted thereon, a locking mechanism comprising two pivoted arms, one of said arms being formed with a bolt portion, and the other with a tumbler engaging portion, means carried by one arm for preventing the said arms from separating to too great an extent, a spring normally tending to separate the outer ends of said arms, a spring normally tending to force the tumbler engaging arm against tumblers, a series of tumblers having recesses formed therein, and means for bringing the recesses into alinement for permitting the tumbler engaging arm to rock so as to withdraw the bolt from the said shackle.

4. A combination padlock mechanism comprising a casing, a pivoted shackle, a bolt having a flange for locking the shackle, a pivot pin carrying said bolt, a lever mounted adjacent to the bolt and having a projection capable of rocking the bolt for withdrawing the same, the said lever also being pivoted on said pivot pin, a spring for normally holding the bolt against the projection of said lever, a series of combination disks having recesses formed therein, a spring fulcrumed in the casing and adapted to press the said lever against the edges of the disks, and a knob mounted exteriorly of the padlock and connected with one of said disks, and projections upon all of said disks co-operating for the movement of the disks by said knob, to bring their depressions in alinement beneath the lever when the bolt is to be withdrawn.

In witness that I claim the foregoing I have hereunto subscribed my name this 28th day of February, 1911.

S. F. HOLMES.
